Patented Mar. 27, 1917.

UNITED STATES PATENT OFFICE.

ALFRED C. O. BOCK, OF BROOKLYN, NEW YORK, ASSIGNOR TO THE YALE & TOWNE MANUFACTURING COMPANY, OF STAMFORD, CONNECTICUT.

LATCH.

1,220,939.

Specification of Letters Patent. Patented Mar. 27, 1917.

Application filed January 25, 1917. Serial No. 144,458.

To all whom it may concern:

Be it known that I, ALFRED C. O. BOCK, a subject of the Emperor of Germany, and a resident of Brooklyn, in the county of 5 Kings and State of New York, have invented certain new and useful Improvements in Latches; and I do hereby declare the following to be a full, clear, and exact description of the invention, such as will 10 enable others skilled in the art to which it appertains to make and use the same.

My invention relates to improvements in latches, and particularly those having double throw bolts, the object being to provide improved means for holding the bolt in its single throw position, which means are released to permit of the full throw of the bolt, by its contact with the strike plate as the door approaches its closed position.

20 A further object is to provide improved means for locking the bolt against retracting movement when in its single throw position.

A further object is to provide means 25 operable from the inside of the door for deadlocking the bolt when in its single throw position, and independent means for deadlocking the bolt in its double throw position, said latter means being operable 30 to release the bolt by the bolt retracting means for the latter.

With these objects in view my invention consists in the parts and combination of parts as will be more fully explained and 35 pointed out in the claims.

In the accompanying drawings, Figure 1 is a view in elevation of the latch, the cover plate of the casing being removed and showing the bolt in its single throw position; Fig. 2 is a similar view of the cover plate and strike plate or keeper; Fig. 3 is a view in elevation showing the bolt in its double throw position; Fig. 4 is a view similar to Fig. 1, showing the bolt deadlocked 45 in its single throw position; Fig. 5 is a view showing the bolt in its retracted position and the means for holding it retracted; Fig. 6 is a view of the bolt; Fig. 7 is a view in perspective of the bolt deadlocking mechanism, and Fig. 8 is a view in section showing the pivoted bolt holding lever holding the bolt in its single throw position.

The improvement is shown in connection with a latch the bolt of which is adapted 50 to be actuated by a key at the outer side of

the door, and by a knob at the inner side, but I would have it understood that I do not confine myself to the details of the mechanism shown, except the bolt and the parts which coact therewith to produce the 60 results hereinafter described.

1 represents the latch casing open at its inner face only, and provided at one end with an opening for the passage of the bolt 2, and also for the reception of the pivoted 65 lever 3, which is provided with a spring 4, the latter normally tending to hold said pivoted lever projected beyond the end of the casing and in a position to engage the strike plate keeper 5 as the door moves to 70 its closed position.

The bolt 2 is provided at its rear end with a rearwardly and laterally projecting lug 6 formed integral therewith. The lug is 75 flush with one face of the bolt, and rests and moves in contact with the inner face of the lock casing 1, and is in a position to be engaged by one side and the free end of the rear arm of the pivoted lever 3.

Projecting from the inner end of the bolt 80 2, are the parallel rods or stems 7, each of which is provided at its rear end with a head 8 projecting at both sides of the stem and engaged on one side by the roll back 9, on the knob stem 10, and on the other 85 side by the roll back 11 journaled in the removable cover plate 12 of the lock casing and actuated by a Yale & Towne key cylinder or other mechanism secured to the door and connected in the usual manner with 90 said roll back 11. The two stems 7 are located centrally with relation to the thickness of the bolt and also to the casing 1, and pass through the cross bar 12 which is supported at its ends against shoulders 13 95 formed on the side members of the casing 1. The stems are encircled by the springs 14, which bear at their front ends against the rear end of the bolt, and at their rear ends against the cross bar 12, and normally 100 tend to hold the bolt in its projected position.

15 is the lever for deadlocking the bolt in its double throw position. This lever is bell crank in shape, and is pivoted at its elbow 105 by the screw 16, to the lock casing 1. The front end of the long arm of this lever terminates near the front end of the casing, and in a position to be moved by the spring to the rear of the bolt when the latter is 110

fully projected, and to ride against the side face of the bolt when the latter is retracted and also partly projected, as is shown in Figs. 1, 4 and 5. The short arm of said lever is provided at its free end with the post 17, which latter, when the bolt is fully projected, rests in the notches 18 in the roll backs 9 and 11, and when so located the free end of the long arm of the said lever is in the path of movement of the bolt at the rear of the latter as shown in Fig. 3, and forms a stop or dead lock for the same. The notches 18 are located centrally in the roll backs, hence when either one is actuated by the knob or key, the side walls of the notches act as cams, thus pushing the post laterally which turns the lever 15 on its fulcrum and moves the free end of its long arm out of the path of movement of the bolt, thus permitting the further or continued turning movement of the roll back to retract the bolt in the usual and well known manner.

The lug 6 on bolt 2, coacts with the pivoted bolt holding lever 3 for holding the bolt in its single throw position. This lever, as before explained is provided with a spring 4, which tends to hold the outer end of the lever projected and in a position to engage the strike plate or keeper 5. When the bolt is in its double throw position, as shown in Fig. 3, the lug 6 rests under the inwardly projecting arm of the lever 3, and as the bolt is pulled inwardly, by either the knob or key, the lug 6 will be moved rearwardly. As the bolt reaches its single throw position the lug passes from under the lever 3 and the latter is then moved by its spring into a position in front of the lug 6 and acts as a stop, and holds the bolt in such position until released by the contact of the outer projecting end of the pivoted lever with the strike plate or keeper 5 during the closing movement of the door thus permitting the bolt, when the door is fully closed, to move forwardly to its double throw position, and when this position is reached, the front end of the long arm of the deadlocking lever 15 passes behind and in the path of movement of the bolt and deadlocks the same.

When the bolt is in its single throw position, the front free end of the dead locking lever 15 bears against the side face of the bolt and does not offer any resistance to the inward movement of the bolt caused by contact of the latter with the strike plate or keeper.

As the bolt is being pushed inwardly by its contact with the strike plate, the pivoted bolt holding lever 3 also engages said strike plate and is turned so as to carry its free end out of the path of movement of the lug 6 on the bolt, so that when the door reaches its closed position, the bolt will be free to move to its double throw position without

any opposition from the bolt holding lever, the latter being held away from and out of the path of the lug, by its contact with the strike plate.

19 is a slide having a finger piece 20 operable from the inner side of the door. This slide is provided with an inwardly projecting stud 21 adapted to be moved in front of the lug 6, on the bolt for holding the bolt in its fully retracted position as shown in Fig. 5; hence by first retracting the bolt by turning the knob, and then shifting the slides until the stud thereon rests in front of lug 6, the bolt will be held retracted until released by shifting the slide to its other position. If desired this slide may be moved, when the door is open, and the bolt in single throw position, in rear of the lug as shown in Fig. 4 and thus prevent the bolt from being forced inwardly as it must be in order to close and lock the door; or after the door has been closed, the bolt may be retracted by the knob or key to its single throw position, and then deadlocked against retraction by the key, by shifting the slide into deadlocking position in rear of the lug 6 as shown in Fig. 5.

It is evident that many slight changes might be resorted to in the relative arrangement of parts shown and described without departing from the spirit and scope of my invention. Hence I would have it understood that I do not wish to confine myself to the exact construction and arrangement of parts herein shown and described, but

Having fully described my invention what I claim as new and desire to secure by Letters-Patent, is:—

1. In a latch, the combination of a double throw bolt having a shoulder at one side, and a lever pivoted to the lock casing and adapted to engage the shoulder on the bolt for holding the latter in its single throw position, the said lever adapted to be turned on its pivot by its engagement with the strike plate as the door is closed so as to release the bolt and permit it to move to its double throw position when the door reaches its closed position.

2. In a latch, the combination of a double throw bolt having a shoulder projecting at one side thereof and a spring pressed lever pivoted to the latch casing and adapted to engage the shoulder on the bolt for holding the latter in its single throw position, the said lever adapted to be turned on its pivot by its engagement with the strike plate as the door is closed, so as to release the bolt and permit it to move to its double throw position when the door reaches its closed position.

3. In a latch, the combination of a double throw bolt, key mechanism for actuating the bolt from the outer side of the door, means for holding the bolt in its single throw posi-

tion, and means for deadlocking it when in such position.

4. In a latch, the combination of a spring actuated bolt, means for retracting the same, 5 a lever pivoted to the latch casing with one end normally projecting to engage the strike plate or keeper of the latch, a projection from the bolt adapted to be engaged by the inner end of said lever whereby the 10 bolt may be held in a partly retracted position when the door is open and a lever for dead locking the bolt when the latter is fully projected.

5. In a latch, the combination of a spring 15 actuated bolt, means for retracting the same,

means for holding the bolt partly retracted, the said means being engaged by the strike plate or keeper of the lock to release the bolt, and means for locking said bolt against retraction by the retracting means and also 20 for holding it in its partly retracted position.

In testimony whereof, I have signed this specification in the presence of two subscribing witnesses.

ALFRED C. O. BOCK.
